UNITED STATES PATENT OFFICE

2,580,547

SELF-CLEANING GAS SAFETY TANK

Joseph D. Hollcroft, Kermit, Tex.

Application December 27, 1946, Serial No. 718,768

2 Claims. (Cl. 210—209)

1

This invention relates to new and useful improvements in storage tanks and more particularly and specifically to self-cleaning gas safety tanks of which the following is a specification.

The primary object of this invention resides in the provision of a storage tank for oil or the like which is provided with a new and improved internal means for cleaning and removing basic sediments and sludge from the bottom of the tank without disturbing or involving the clean oil or fluid stored therein.

Another object of this invention is the provision of a tank cleaning means which is completely and wholly operated from without the tank to clean and drain the undesirable elements therefrom with the cleaning and draining operation being carried on completely within the tank without the necessity of opening and draining the operation.

Still another object of this invention is the provision of a safe and accurate gauging means for the tank which is so constructed as to eliminate the possibility of a gaseous discharge from the tank onto the person opening the tank for gauging purposes.

Still a further object of this invention is the provision of a tank and apparatus therefor which is of extremely simple and inexpensive design and which is durable and long lasting in use.

Still further improvements and advantages of this invention will readily appear to those skilled in the art when the following description is read in the light of the accompanying drawings in which:

Fig. 1 is a top plan view of the tank.

Fig. 2 is a vertical section taken on line 2—2 of Fig. 1.

Fig. 3 is a horizontal cross section taken on line 3—3 of Fig. 2.

Fig. 4 is an enlarged partial section of cleaning supply line.

Referring now to the accompanying drawings which illustrate the preferred embodiment of this invention and in which like numerals indicate similar parts throughout A designates a large storage tank for crude oil or the like which is supported on stilt legs 1 or the like at a spaced distance above the ground. The tank A includes a cylindrical upstanding wall and has an elevated cone-like top 2 formed thereon and a depending or inverted cone-like bottom 3 also formed therewith.

The top 2 is provided with a filling valve 4 secured thereto by flanges 5 secured internal and external the filling tube 6 which penetrates the

2

top 2. A vertical vent pipe 7 opening the interior of the tank outwardly through the top 2 is provided at one point in the top to pass off the gases caused by the evaporation of the contents of the tank and to allow an air escape when the tank is being filled.

A pivoted hatch cover 8 is hinged at the top center of the tank top in a covering position over a hatch 9 extending downwardly into said tank, and a standard vertical rung ladder 10 is secured within said hatch to extend downwardly to be supported at its base in a centered position on the cone-like bottom 3 of the tank.

An elongated hollow gauge tube 11 is secured 15 downwardly through the top 2 of the tank to extend vertically downward within said tank, at a spaced distance inward from the wall thereof, to a spaced distance above the bottom of said tank.

The bottom of the tube 11 is open while the 20 top is provided with a hinged cover 12 thereon without the top of said tank. This tube allows for the gauging of the depth of the oil within said tank without allowing a discharge of gases through said tube whose lower end is immersed 25 in oil preventing the entrance of such gases therinto, and said tube being adjacent one wall of said tank provides for a gauging of the good oil in the tank without including the depth of the basic sediments and sludge which form and collect in the depending center inward from beneath the open end of the tube.

An inlet pipe line 13 for air, gas, water or the like enters the tank at one point in the joint of said tank and tank bottom where it meets a circular pipe 14 which lies flush with the outer circumference of the cone bottom concentric therewith. This circular pipe is provided with a plurality of spaced alternate length extensions 15 which radiate inward therefrom toward the center of the cone bottom being in an adjacent downhill position therewith. The inward end of these extensions 15 are provided with nozzle-like openings 16 adapted to direct a stream discharge therethrough of the fluent material admitted through said inlet pipe under pressure thus forming a swirling vortex about the center of the cone bottom 3 causing a loosening and flushing of the basic sediment and sludge therein which drains downwardly to the center thereof and out through a drainpipe 17 opening upwardly in the center of the tank bottom.

A cone plate or baffle 18 is secured horizontally to the lower end of the ladder 10 as at 19 at spaced distance above the center of the tank bottom. The outer edge of this cone plate 18

extends beyond the inner end of the longest of the extensions 15 and act to prevent the vortex from penetrating upwardly through the basic sediment into the good oil or the like thereabove and thus preventing the wasteful drainage thereof.

Thus it may be seen that a storage tank with an improved cleaning and safe and accurate gauging means has been provided.

Having thus described and explained the construction and operation of this invention and with full belief that modifications in size, materials and general characteristics would not constitute a departure from the spirit of this invention what I desire to claim in Letters Patent is:

1. A tank for storing crude oil or the like comprising a bottom in the form of an inverted cone, an upstanding wall super-imposed upon said inverted cone and secured thereto, a horizontally disposed circular pipe positioned within said inverted cone adjacent to and spaced from the upper end thereof and resting upon said cone, a pipe having one end extending through said upstanding wall and connected to said circular pipe for delivering fluid under pressure to the latter pipe, a plurality of pipes arranged at an angle with respect to and within said circular pipe and each having one end connected to said circular pipe, said plurality of pipes extending in radial spaced relation about the inner-periphery of said circular pipe and resting upon said inverted cone, the other ends of said plurality of pipes being each provided with a nozzle and spaced from the apex of said inverted cone, a drain pipe exteriorly of said inverted cone and having one end connected to the apex of said cone for withdrawing sediment suspension fluid from said tank, and a fixed conically shaped baffle positioned within said circular pipe and in alignment with the apex of said inverted cone and having its bounding edge spaced from the plurality of pipes.

2. A tank for storing crude oil or the like comprising a bottom in the form of an inverted

cone, an upstanding wall superimposed upon said inverted cone and secured thereto, a horizontally disposed circular pipe positioned within said inverted cone adjacent to and spaced from the upper end thereof and resting upon said cone, a pipe having one end extending through said upstanding wall and connected to said circular pipe for delivering fluid under pressure to the latter pipe, a plurality of pipes arranged at an angle with respect to and within said circular pipe and each having one end connected to said circular pipe, said plurality of pipes extending in radial spaced relation about the inner-periphery of said circular pipe and resting upon said inverted cone, the other end of said plurality of pipes being each provided with a nozzle and spaced from the apex of said inverted cone, some of said plurality of pipes being shorter in length than other of said plurality of pipes, a drain pipe exteriorly of said inverted cone and having one end connected to the apex of said cone for withdrawing sediment suspension fluid from said tank, and a fixed conically shaped baffle positioned within said circular pipe and in alignment with the apex of said inverted cone and having its bounding edge spaced above said nozzles.

JOSEPH D. HOLLICROFT.
